UNITED STATES PATENT OFFICE.

ELMER C. BLACKWELL, OF SALEM, MISSOURI.

PROPELLER.

1,159,824.

Specification of Letters Patent. Patented Nov. 9, 1915.

Application filed May 9, 1914. Serial No. 837,475.

To all whom it may concern:

Be it known that I, ELMER C. BLACKWELL, citizen of the United States, residing at Salem, in the county of Dent and State of Missouri, have invented certain new and useful Improvements in Propellers, of which the following is a specification.

My invention relates to an improved aeroplane propeller.

10 The invention consists essentially in the provision of a plurality of radially disposed propeller blades, so constructed and arranged relatively to operating means therefor as to be bodily shifted or moved, 15 such movement, as will appear hereinafter, causing little or no resistance to be offered by the atmosphere in one position of the blade, and a full resistance to be offered in a second position of the blade, this particular 20 operation serving to increase the propelling force derived through rotation of the propeller.

25 The primary object of the invention contemplates means including a plurality of actuating disks so arranged relatively to the spindles of the several propeller blades as to engage lugs thereupon, the engagement between the said lugs and the said disks providing for automatic movement of the 30 blades while rotating.

A further object of the invention resides in the provision of a novel and peculiarly formed propeller blade support.

35 The above and additional objects are accomplished by such means as are illustrated in their preferred embodiment in the accompanying drawings, described in the following specification and then more particularly pointed out in the claims which are appended hereto and form a part of this application.

40 In describing my invention in detail reference will be had to the accompanying drawings wherein like characters denote like or corresponding parts throughout the several views, and in which:—

45 Figure 1 is a face view of a propeller constructed in accordance with the present invention; Fig. 2 is a similar view, one of the 50 actuating disks having been removed; Fig. 3 is a section on the line 3—3 of Fig. 1; Fig. 4 is a face view of one of the actuating disks; Fig. 5 is a similar view of the propeller blade support; Fig. 6 is a fragmentary view illustrating the arrangement of the lugs upon one of the propeller blade

spindles; and Fig. 7 is a similar view taken at an angle to that of Fig. 6.

Before proceeding with the description of the drawings, I desire to call particular attention to the fact that while I have evolved my invention with reference to its application in connection with aeroplanes, the same may be readily utilized as a means whereby movement may be imparted to boats, vehicles and other propelled devices susceptible of its application.

Referring now to the drawings by numerals, 1 designates the propeller shaft upon which is mounted a propeller, designated as 2. Said propeller in its preferred embodiment includes a plurality of radiating blades 3, each of which is provided with a spindle 4 journaled as at 5 within bearings carried by a supporting ring designated 6. The manner in which the supporting ring 6 is constructed is best illustrated in Fig. 5. Lugs 7 radiate from a hub or center of the ring 6, one lug being axially alined with each bearing 5, 80 this arrangement providing for the reception of the said lugs within recesses 8 formed in the ends of the several spindles.

Actuating disks, designated respectively 9 and 10 are arranged, one upon each face of the supporting ring 6, the actuating disk 9 upon the outer face of the ring being provided with a sleeve like extension 11 arranged to embrace the said shaft 1. Disk 10 is also provided with a sleeve like extension designated 12, the latter embracing a sleeve 13 integral with the supporting ring 6, which latter sleeve, as illustrated to advantage in Fig. 3, is arranged to embrace the sleeve 11 of the disk 9. A gear 14 is mounted upon sleeve 11 for rotating the said sleeve independently of the shaft 1. A second gear 15 is mounted upon sleeve 13 for imparting to the said sleeve the rotary movement necessary to the proper operation of the propeller. A third gear 16 is mounted upon sleeve 12 for actuating said disk 10 independently of the propeller, the purpose of actuating the disks 9 and 10 to be herein-after fully described.

105 Disks 9 and 10 are each provided with a semicircular ring 17, the said rings being supported in spaced relation to the main or body portion of the disk through the medium of strips 18, preferably arched, to provide for the operation of lugs 19 and 20 as will hereinafter appear. Shoulders 21

are formed at the respective terminals of the ring 17, which shoulders, together with shoulders 22 formed adjacent thereto but out of circumferential alignment, are adapted for engagement with the lugs 19 and 20 to provide for the shifting movement of the propeller blade 3 as the propeller is rotated.

Operation of the device is as follows: Disks 9 and 10 being arranged as illustrated to advantage in Figs. 1 and 2, it is apparent that the lugs 19 and 20 will engage the shoulders 21 and 22 as the propeller blades 3 rotate with the propeller, and as the said lugs 20 engage the shoulders 22, it is apparent that the blades 3 will be shifted or rotated whereby to assume the position illustrated in Fig. 1. By a continued rotation of the blades until lugs 19 engage shoulders 21, blades are again given a half turn, such movement of the blades being automatic and positive. When it is desired that the place at which the feathering action occurs be changed, each disk 9 and 10 is given a half turn. As the ring 6 is rotated, the lugs on the spindles engage the shoulders 21 and 22, such engagement causing the blades to be individually oscillated, the inner lugs 19 working in the space between the disk 9 and the semi-circular ring 17 in one position of the ring 6 and the lugs 20 working in the space beyond the periphery of the disk 9, the respective lugs being engageable with the respective shoulders for imparting the proper oscillatory movement to the blades.

From the foregoing, taken in connection with the accompanying drawings it is apparent that the blades will shift automatically to offer a full amount of resistance to the atmosphere in one position and to offer little or no resistance in a second position, this operation serving to increase the propelling force to a material extent; that by the provision of the arched strips 18, the operation of the lugs 20 will in no way be impeded; and that by journaling the spindles 4 as indicated at 5, and arranging the several lugs 7 within the recesses 8 therefor, the blades are so mounted as to be bodily shifted from a position at right angles to the axis of rotation of the propeller shaft to a position parallel with the said axis of rotation, this shifting operation being illustrated clearly in Fig. 1.

In reduction to practice, I have found that the form of my invention, illustrated in the drawings and referred to in the above description, as the preferred embodiment, is

the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:

1. In a propeller, a rotatable element comprising a hub, spokes, and rims, radial lugs formed on the hub, a plurality of blade arms, each having a socket formed therein to receive the radial lugs, bearings formed on the rim to engage the arms, flanges formed on the arms to engage the rim, means to rotate the element, and means to feather the blades while rotating.

2. In a propeller, a sleeve like shaft, means to rotate the shaft, an element rotatable with the shaft, the element comprising a hub, spokes, and rims, radial lugs formed on the hub, a plurality of blade arms, each having a socket formed therein to receive the radial lugs, bearings formed on the rim to engage the arms, flanges formed on the arms and engaging the rim, a disk arranged upon each of the respective lateral faces of the blade carrying element to feather the blades while rotating, means fitting the sleeve like shaft and having connection with one of said disks to rotate it, and means embracing said sleeve like shaft and having connection with the other of the said disks to rotate it simultaneously through rotation of the disk last mentioned.

3. In a propeller, a shaft, a disk mounted on said shaft, a sleeve, a duplicate disk mounted on said sleeve and disposed in proximity to said first mentioned disk but in spaced relation thereto, a second sleeve inclosed by said first sleeve and inclosing said shaft, a propeller mounted on said last mentioned sleeve to rotate between said disks, a means to rotate the shaft and said sleeve, and a means on the propeller engaging said disks to feather the propeller blades.

In testimony whereof I affix my signature in presence of two witnesses.

ELMER C. BLACKWELL.
